UNITED STATES PATENT OFFICE.

JAMES H. TURBUSH, OF NEW YORK, N. Y.

TRAIN AIR-SIGNALING APPARATUS.

SPECIFICATION forming part of Letters Patent No. 659,904, dated October 16, 1900.

Application filed December 18, 1899. Serial No. 740,705. (No model.)

To all whom it may concern:

Be it known that I, JAMES H. TURBUSH, a citizen of the United States, and a resident of the city of New York, borough of Bronx, in 5 the county and State of New York, have invented, a new and Improved Train Air-Signaling Apparatus, of which the following is a full, clear, and exact description.

The invention relates to fluid-pressure brakes of the Westinghouse type; and its object is to provide a new and improved train air-signaling apparatus whereby the separate signal-pipe now used is dispensed with and the train-pipe and its pressure, as well as the 10 engineer's valve, are made use of to actuate the whistle and give the desired signals to the engineer by the conductor of the train no matter what position the engineer's valve is in.

The invention consists of novel features 15 and parts and combinations of the same, as will be fully described hereinafter and then pointed out in the claims.

A practical embodiment of my invention is 20 represented in the accompanying drawings, forming a part of this specification, in which similar characters of reference indicate corresponding parts in all the views.

Figure 1 is a perspective view of the improvement with part of the signaling-valve 25 in section. Fig. 2 is an enlarged sectional side elevation of the duplex engineer's valve in releasing position, the section being on the lines 2 2 in Figs. 3 and 5. Fig. 3 is a sectional plan view of the same on the line 3 3 in Fig. 30 4. Fig. 4 is a sectional side elevation of the same on the lines 4 4 in Figs. 3 and 5, and Fig. 5 is a plan view of the rotary valve.

In my improved train air-signaling apparatus the ordinary train-pipe A of the fluid-pressure brake is made use of as a signaling-pipe besides the usual function that such pipe has in the brake. In each car in a train is arranged a branch pipe B, connected with the train-pipe A, and on this branch pipe B is arranged the usual car discharge-valve C, as indicated in Fig. 1, the valve being under the control of the conductor to give the desired signals to the engineer, as hereinafter more fully explained. The train-pipe A connects 45 50 with the duplex engineer's valve D, connected by a pipe E with the main reservoir, and said duplex engineer's valve is provided with the

usual handle 8, under the control of the engineer, to turn the rotary valve 14 and bring the latter into the various positions for operating the brake in the usual manner, said rotary valve operating over the rotary-valve seat 3, which has duplicate ports to correspond with similar duplicate ports in the rotary valve 14. The train-pipe A is connected by 55 a pipe F with a signaling-valve G having two compartments G' G², separated from each other by a diaphragm or piston valve G³, carrying on its stem G' a valve G⁵, normally seated on a valve-seat G⁶, contained in the lower 60 compartment G², connected by a pipe H with the duplex engineer's valve by the piston-valve 18^a, which is a counterpart of the usual piston-valve 18 of the brake mechanism, (see Fig. 2,) said piston-valve 18^a simultaneously 65 operating with and in exactly the same manner as the piston-valve 18 of the brake mechanism, it being understood that the rotary valve 14, its duplicate ports, and the duplicate ports in the seat 3 permit such movement of the piston-valves 18 and 18^a, whereby 70 the same pressure is maintained in both compartments G' and G² no matter what position the rotary valve 14 is in, and consequently 75 the valve G⁵ is firmly held to its seat and is thus in a closed position when the engineer uses the engineer's valve for its legitimate purposes—that is, for applying or releasing the brakes. The valve-seat G⁶ is connected with a pipe I, carrying a whistle J of any approved construction.

When the conductor opens one of the valves C in the train and makes a reduction of pressure in the train-pipe A, then a similar reduction of pressure takes place in the upper 90 compartment G', owing to the latter's connection with the train-pipe by the pipe F. The preponderance of pressure in the lower compartment G² now causes the diaphragm G³ to move upward, whereby the valve G⁵ is lifted off its seat, and air from the compartment G² 95 can pass through the pipe I to the whistle J and sound the same. This small reduction of pressure in the train-pipe does not affect the triple valves in any manner, as the engineer does not change the position of the engineer's valve, nor is the position of the engineer's valve changed during the signaling, as 100 described, and consequently the position of

the brake mechanism as such is not disturbed while the signaling through the train-pipe is taking place.

From the foregoing it is evident that it does not make any difference in what position the engineer's valve is, as it is in communication at all times, especially between the train-pipe A and the upper compartment G' of the signaling-valve G, and communication is established between the lower compartment G² and the main reservoir by way of the duplex engineer's valve D. It is also understood that the duplex engineer's valve equalizes the pressure in the compartments G' G², so that the valve G⁵ is firmly closed. Thus the engineer's valve equalizes the pressure between the main reservoir and the train-pipe on one hand and between the main reservoir and the lower compartment G² on the other hand, so that whatever pressure is in the train-pipe A is in the lower compartment G², unless a reduction of pressure takes place by the conductor operating the car discharge-valve C. Thus as long as there is fluid-pressure in the train-pipe the whistle can be sounded—that is, signals can be passed from the conductor to the engineer.

By reference to Fig. 1 it will be seen that the duplex engineer's valve is provided with two reducing-valves K and K', one for the train-pipe pressure and the other for the pressure in the pipe H, to allow of maintaining at the same time different pressures in the pipes, if found necessary for the proper working of the brake and the signaling apparatus.

Having thus fully described my invention, I claim as new and desire to secure by Letters Patent—

1. In a train air-signaling apparatus in which the train-pipe is used as a signaling-pipe, a duplex engineer's valve provided with duplicate pistons and a duplex valve controlling said pistons, and a signal-actuating mechanism connected with the whistle and including a pneumatically-operated valve,

the pistons operating upon opposite sides of said pneumatically-operated valve as set forth.

2. In a train air-signaling system in which the train-pipe is used as a signaling-pipe, a signal-actuating mechanism consisting of a casing connected with the whistle and a diaphragm-valve in said casing and controlling said whistle, and an engineer's brake-valve provided with duplicate pistons and a duplex valve controlling said pistons, the latter operating upon opposite sides of the diaphragm-valve as set forth.

3. In a train air-signaling apparatus in which the car discharge-valve is connected with the train-pipe and the latter is used as a signaling-pipe, a signal-actuating mechanism consisting of a casing and a diaphragm-valve dividing said casing into two compartments, one of said compartments being connected with the whistle and the diaphragm-valve controlling the operation of the whistle, a duplex engineer's brake-valve having two pistons, a connection between the lower compartment of the casing and one part of the engineer's valve, and a connection between the other compartment and the train-pipe through the other part of the engineer's valve, as set forth.

4. A fluid-pressure brake and train air-signaling apparatus having a duplex engineer's valve arranged to connect the main reservoir with the signal-valve, said engineer's valve comprising two piston-valves, and a rotary valve under the control of the engineer, substantially as shown and described.

In testimony whereof I have signed my name to this specification in the presence of two subscribing witnesses.

JAMES H. TURBUSH.
